UNITED STATES PATENT OFFICE.

ASHBY STEWART RECE, OF HUNTINGTON, WEST VIRGINIA.

LOCOMOTIVE-TORCH.

1,156,097.

Specification of Letters Patent.

Patented Oct. 12, 1915.

Application filed February 24, 1915. Serial No. 10,329.

To all whom it may concern:

Be it known that I, ASHBY S. RECE, a citizen of the United States, residing at Huntington, in the county of Cabell and State of West Virginia, have invented a new and useful Locomotive-Torch, of which the following is a specification.

The device forming the subject matter of this application is a torch of that general form which is used upon locomotive engines and elsewhere.

The invention aims to provide a torch of the type above described embodying a wick tube which may be telescoped readily within the receptacle portion of the torch, thereby to economize space when the torch is not in use, it being possible to seal the torch effectively and permanently when the same is not in use, so that the oil in the torch will not leak away.

It is within the province of the disclosure to improve generally and to enhance the utility of devices of that type to which the present invention appertains.

With the above and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed, without departing from the spirit of the invention.

In the accompanying drawing:—Figure 1 is a vertical longitudinal section, the torch being closed and the wick tube being telescoped; Fig. 2 is a fragmental longitudinal section wherein the torch appears in the condition it will assume when in use, the wick tube being extended.

In carrying out the present invention there is provided a receptacle 1 having a handle 2, and a neck 3 including a rigidly mounted internal thimble 4. At its outer end, the thimble 4 is equipped with a laterally extended flange or shoulder 5 extended entirely around the neck. The thimble 4 is provided with internal threads 6.

Mounted to reciprocate vertically within the contour of the thimble 4 is a tube 7 through which a wick 8 passes. To the lower end of the wick tube 7 is secured a collar 9 having external threads 10 and provided at its lower end with an outstanding flange or shoulder 11,

The invention includes a cap 12 provided intermediate its ends with an outstanding flange 14, the cap being externally threaded below the flange 14 as shown at 15. Secured to the under face of the flange 14 is a gasket or washer 17. Extended downwardly through the thimble 4 is a duct 16.

When the torch is not in use, the parts thereof appear as shown in Fig. 1, the wick tube 7 being telescoped into the receptacle 1, the threads 15 of the cap 12 being engaged with the threads 6 of the thimble 4, and the gasket 17 being tightly pressed against the flange or shoulder 5 of the thimble 4 by the flange 14 on the cap 12. It will be seen that when the parts are arranged as above described, the torch occupies but a minimum amount of space. Further, the receptacle 1 is hermetically sealed, so that the oil in the receptacle cannot leak out, the gasket 17 covering the duct 16 and effectively closing the same.

When it is desired to use the torch, the cap 12 is threaded out of the thimble 4 and the wick tube 8 is elevated, the threads 10 on the collar 9 of the wick tube being engaged with the threads 6 in the thimble 4 of the neck 3, and the flange or shoulder 11 on the collar 9 being in abutment with the lower end of the thimble 4 to afford an oil tight joint. The diameter of the flange 11 is sufficiently small so that when the flange is in abutment with the lower end of the thimble 4 as shown in Fig. 2, the duct 16 is not cut off and therefore air may find its way into the receptacle 1 on top of the oil therein.

Having thus described the invention, what is claimed is:

1. A torch of the class described comprising a receptacle; a wick tube mounted to reciprocate in the receptacle; interengaging elements on the lower end of the wick tube and on the receptacle for holding the wick tube elevated; and a cap adapted to cover the upper end of the wick tube when the tube is telescoped into the receptacle, the cap and the receptacle being provided with interengaging elements.

2. In a torch of the class described, a receptacle provided at its upper end with internal threads; a tube slidable in the receptacle and provided at its lower end with external threads adapted to engage the threads of the receptacle; and a cap housing the upper end of the tube when the

tube is telescoped into the receptacle, the cap having external threads adapted to engage the threads of the receptacle.

3. In a torch of the class described, a
5 receptacle including a neck having a duct;
a wick tube slidable in the neck, the wick
tube and the neck being provided with in-
terengaging elements for holding the wick
tube elevated; and a cap for the upper end
10 of the wick tube, the cap and the neck being
provided with interengaging elements, a
portion of the cap constituting a closure for
the duct when the cap is in place.
4. In a torch of the class described, a
15 receptacle comprising a neck having a duct;
a tube slidable in the neck, the lower end
of the tube and the neck having interen-

gaging elements adapted to hold the tube
elevated, the tube being provided at its
lower end with an outstanding flange co-
20 acting with the neck to limit the upward
movement of the tube, the inner end of the
duct opening into the receptacle between
the wall of the receptacle and the periphery
25 of the flange when the flange coacts with
the neck.

In testimony that I claim the foregoing
as my own, I have hereto affixed my signa-
ture in the presence of two witnesses.

ASHBY STEWART RECE.
